United States Patent Office

Des. 201,243
Patented June 1, 1965

201,243

BUTTON

Robert B. Moise, P.O. Box 1442, Sumter, S.C.

Filed Sept. 18, 1963, Ser. No. 76,629

Term of patent 14 years

(Cl. D17—2)

FIG. 1

FIG. 2

FIG. 3

FIG. 1 is a top perspective view of a button embodying my new design;

FIG. 2 is a bottom perspective view; and

FIG. 3 is a sectional view thereof taken on the line 3—3 of FIG. 1.

I claim:

The ornamental design for a button, as shown.
